UNITED STATES PATENT OFFICE

128,152

DESIGN FOR A BATTERY CASE

Egmont Arens, New York, N. Y., assignor to Atlas Supply Company, Newark, N. J., a corporation of Delaware

Application May 17, 1941, Serial No. 100,991

Term of patent 3½ years

To all whom it may concern:

Be it known that I, Egmont Arens, a citizen of the United States, residing at New York, in the county of New York and State of New York, have invented a new, original, and ornamental Design for Battery Cases, of which the following is a specification, reference being had to the accompanying drawings, forming part thereof.

In the drawings:

Fig. 1 is a front elevational view of a battery case showing my new design.

Fig. 2 is an elevational view showing one end of the battery case.

Fig. 3 is a rear elevational view.

Fig. 4 is a view similar to Fig. 2, but showing the design at the opposite end of the battery case.

The top of the battery case of the design is conventional.

I claim:

The ornamental design for a battery case, as shown and described.

EGMONT ARENS.
